CLAIM

The ornamental design for a toy as shown and described.

DESCRIPTION

FIG. 1 is a front top perspective view of a toy showing our new design;

FIG. 2 is a front bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines depict portions of the toy that form no part of the claimed design. As an example, the design may be implemented as a toy replica of a pistol.
